L. E. SPRAY

THERMO-SENSITIVE RELAY

Filed Sept. 26, 1922

FIG.1.

FIG.2.

FIG.3.

INVENTOR:

Lester E. Spray,
by A. Z. Venaille,
His attorney.

UNITED STATES PATENT OFFICE.

LESTER E. SPRAY, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

THERMOSENSITIVE RELAY.

Application filed September 26, 1922. Serial No. 590,726.

My invention relates to thermo-sensitive relays, that is, relays which depend for their action upon changes in the electrical characteristics of a substance in response to changes in temperature. One feature of my invention is the provision of a relay of this character adapted to control a plurality of secondary circuits.

I will describe three forms of relays embodying my invention, and will then point out the novel features thereof in a claim.

In the accompanying drawings, Fig. 1 is a view showing in vertical longitudinal section one form of thermo-sensitive relay embodying my invention. Fig. 2 is a view showing in vertical longitudinal section a modified form of relay also embodying my invention. Fig. 3 is a view showing in vertical section still another form of relay embodying my invention.

Similar reference characters refer to similar parts in each of the three views.

Referring first to Fig. 1, the reference character A designates a heating element comprising a conductor of suitable material such as nichrome. This heating element is provided with a primary circuit including a source of energy such as a battery B, and a switch S. Surrounding this heating element A is a layer or coating of insulating material D such as porcelain or glass. Supported on this insulating material D are a plurality of secondary units K each comprising a cylindrical element C of thermo-sensitive substance having either a positive or a negative temperature coefficient such for example, as copper oxide. A contact band E of some electro-conducting material, such as copper, is placed about one end of each thermo-sensitive element C in contact therewith and serves as a terminal for connection to an external circuit. Surrounding the other end of each thermo-sensitive element C and spaced from the band E is another similar band G. Each secondary unit K is provided with a secondary circuit which passes from the left hand terminal of a battery H through contact rod E, thermo-sensitive element C, contact band G, a lamp J back to the right hand terminal of the battery H. The relay operates in precisely the same manner as the one shown in Fig. 1.

The operation of the relay is as follows: I will assume that the substance C has a

negative temperature coefficient. With the switch S open, the resistance of each element C is so great that it does not allow enough current to pass to light the associated lamp J. When the switch S is closed, the battery B supplies current to the heating element A producing heat which is transmitted through the insulating material D to the thermo-sensitive elements C. The increased temperature of each of these elements causes its resistance to be decreased and the current which then passes through it and the associated lamp J from the battery H is enough to light the lamp which remains lighted as long as the element C remains hot. When the switch S is opened, temperature of the relay decreases and the resistance of each of the thermo-sensitive elements increases causing a corresponding decrease in the current supplied to the lamps J which then become extinguished.

In Fig. 2, which shows a modification of the relay described above, the insulating material is made in the form of a cylinder D in which a plurality of secondary units K are imbedded. Each of these units, thus insulated from the others, comprises a cylindrical element C of thermo-sensitive substance, a contact rod imbedded in the center of this element and protruding from the relay either at the end or on the side so as to offer a terminal for connection to a secondary circuit, and a contact band G surrounding a portion of the element C and having an outstanding lug G' which protrudes through the insulating material D. Wound on the outside of the insulating cylinder D is a heating element A comprising a coil of wire provided with a primary circuit including a battery B and a switch S. Each secondary unit is provided with a circuit which passes from the left hand terminal of a battery H through contact rod E, thermo-sensitive element C, contact band G, a lamp J back to the right hand terminal of the battery H. The relay operates in precisely the same manner as the one shown in Fig. 1.

Fig. 3 shows another modification of the relay. A heating element A is wound in a coil upon a tube D of insulating material, and then a coating D' of insulating material is placed on the coil, making a rigid tube of insulation having the heating element im-

bedded therein. Mounted on this tube are a plurality of secondary units K each comprising a contact band E directly surrounding the insulating tube, an annular element C of thermo-sensitive substance surrounding band E, and another contact band G surrounding the thermo-sensitive element C. A battery H and a lamp J are connected in series with the two contact bands E and G, thus completing, with the thermo-sensitive element C, the secondary circuit. A battery B, controlled by a switch S, supplies current to the heating element A. When the switch is closed the battery B energizes the heating element A, producing heat which is transmitted through the insulating material D and D' and the bands E to the thermo-sensitive elements C. The resulting decrease in the resistance of each element C causes each lamp J to become lighted. When the switch S is opened, the temperature of the relay decreases and the lamps J become extinguished as in Fig. 1.

In each form of relay shown herein the parts are so proportioned that the relation between the applied voltages and the temperature of each thermo-sensitive element is such that the changes in the conductivity of the thermo-sensitive element are due almost entirely to changes in the temperature of the heating element A and are sensibly independent of temperature variations due to the secondary current carried by the thermo-

sensitive element, so that under no circumstances can the heated condition of the thermo-sensitive element be maintained by the secondary current. That is to say, the proportioning is such that the secondary current can have relatively little effect in determining the temperature and so the conductivity of the thermo-sensitive element. In so far as dimensions enter into the matter, each thermo-sensitive element preferably has a comparatively short path of comparatively large area.

Although I have herein shown and described only three forms of relays embodying my invention, it is understood that various changes and modifications may be made therein within the scope of the appended claim without departing from the spirit and scope of my invention.

Having thus described my invention, what I claim is:

A thermo-sensitive relay comprising a secondary unit made up of a cylindrical element of thermo-sensitive substance and spaced contact bands surrounding said thermo-sensitive element, and a primary element made up of a rod of electro-conducting material and a coating of electro-insulating material deposited thereon, said primary element being inserted in a hole in said secondary element.

In testimony whereof I affix my signature.
LESTER E. SPRAY.
